UNITED STATES PATENT OFFICE.

JOHN W. GATES, OF SWIFTON, ARKANSAS, ASSIGNOR OF ONE-HALF TO C. M. SEARCY,
OF SWIFTON, ARKANSAS.

SADIRON.

1,391,888.

Specification of Letters Patent. Patented Sept. 27, 1921.

Application filed May 18, 1920. Serial No. 382,210.

To all whom it may concern:

Be it known that I, JOHN W. GATES, a citizen of the United States, residing at Swiftont, in the county of Jackson and State 5 of Arkansas, have invented a new and useful Sadiron, of which the following is a specification.

This invention relates to self heating sad irons, one of its objects being to provide a 10 device of this character the body portion of which is reversible at will, there being a burner located within the body of the sad iron for heating the upper surface of said body while the lower surface is being used, 15 it being possible subsequently to reverse the body so as to bring the heated surface lowermost while the cooled surface is thus brought into position to be again heated.

A further object is to provide a heater 20 having novel means whereby the size of the flame can be controlled easily.

Another object is to provide a structure of this character which is simple, durable and compact and can be manipulated 25 readily.

With the foregoing and other objects in view, which will appear as the description proceeds, the invention resides in the combination and arrangement of parts and in 30 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a vertical longitudinal section 40 through the device, parts being shown in elevation.

Fig. 2 is a section on line 2—2, Fig. 1.

Referring to the figures by characters of reference 1 designates the body of the sad iron the same being of the usual configuration and having its top and bottom faces duplicates and both adapted to be used as smoothing surfaces. A tube 2 is extended into the back end of the body at the center 50 thereof and constitutes a bearing on which said end of the body 1 will rotate, said tube projecting into an arm 3 provided at one end of a handle 4. Another arm 5 is extended from the other end of the handle and 55 has a pivot screw or pin 6 extending there-

from and into the nose of the body 1. Thus the body is free to rotate between the arms 3 and 5 so as to bring either of its smoothing surfaces into active position. One wall of the body has an opening 7 adapted to be 60 closed normally by a removable door 8, there being lugs 9 upon the door for straddling the wall of the opening and a button 10 for fastening the door in closed position.

Pivotedly mounted on the arm 5 is a lever 65 11 from one end portion of which extend parallel pins 12. These pins work in openings 14 formed in the lower portion of the arm 5 and are adapted to project into openings 15 formed in the nose of the body 1 so 70 as to hold the body with either of its smoothing faces in active position. A spring 16 engaging the lever holds the pins 12 normally projected into the body 1.

Slidably mounted within the tube 2 is a 75 wick tube 17 the outer end portion of which is curved upwardly as indicated at 18 and projects into and supports a container 19 having a closure 20 on the top thereof. A wick 21 is seated in the tube 18 and hangs 80 downwardly within the container 19, the other end of the wick projecting a short distance beyond that end of the tube 17 within the body 1.

A hand shield 22 is secured to the arms 3 85 and 5 and under the handle 4 so that the hand cannot be overheated. Ventilating openings 23 are formed in the body 1 close to the smoothing faces thereof.

When it is desired to use this device the 90 door or closure 8 is removed and the wick, exposed in the body, is ignited. This wick is constantly supplied with alcohol or other liquid fuel in the tank or container 19 and the flame rising from the wick will heat the 95 upper surface of the body 1 as will be obvious. A set screw 24 extends through the lower portion of the handle 3 and through the tube 2 secured in the handle and is adapted to bind upon the wick tube 17 so as 100 to hold it against movement relative to the tube 2.

After the upper surface of the body has been heated to a desired temperature the 105 lever 11 is shifted so as to release the body 1. Said body is then given a one-half rotation, bringing the heated smoothing surface lowermost and bringing the cool smoothing surface to position above the flame where it will be reheated. By unscrewing the set 110

screw 24 and shifting the tube 17 longitudinally within the tube 2, the size of the flame produced at the inner end of the tube 2 can be increased or reduced as desired.

5 By so constructing the device that the upper surface of the body is heated while the sad iron is in use, there is no danger of the lower or smoothing surface becoming overheated and scorching the fabric on 10 which it rests. Instead this lower surface gradually cools while the upper surface is being heated.

What is claimed is:

A self heating sad iron including a body, 15 a handle, arms extending from the handle, a pivotal connection between one end of the body and one of the arms, a tube fixedly connected to the other arm and projecting into the body to constitute a bearing for 20 the other end of the body, a wick tube slidably mounted in the bearing tube and hav-

ing that end thereof within the body rounded and provided with a top opening for a wick, said tube being slideable bodily within the bearing tube to fit the opening relative 25 to the inner end of the bearing tube, a fuel container mounted on the wick tube and supported solely thereby, and means carried by the bearing tube for engaging the wick tube to hold said wick tube against movement relative to the handle and its arms and for fastening the bearing tube to one of the arms, and means for securing the body against rotation upon the bearing tube and relative to the arms.

In testimony that I claim the foregoing as my own, I have hereto affixed my signature in the presence of two witnesses.

JOHN W. GATES.
